UNITED STATES PATENT OFFICE.

ARTHUR H. IVES, OF MINNEAPOLIS, MINNESOTA.

DESIGN FOR A COVER FOR ICE-CREAM TUBS.

SPECIFICATION forming part of Design No. 29,411, dated September 27, 1898.

Application filed June 20, 1898. Serial No. 684,005. Term of patent 7 years.

To all whom it may concern:

Be it known that I, ARTHUR H. IVES, of 5
Minneapolis, county of Hennepin, State of
Minnesota, have invented a certain new and
original Design for Ice-Cream-Tub Covers, of
which the following is a specification, refer-
ence being had to the accompanying draw-
ings, forming a part hereof.

In the drawings, Figure 1 is a perspective 10
view of the top of a cover embodying my
design. Fig. 2 is a similar view of the bottom of
the cover. Fig. 3 is a vertical sectional view.

The design consists in a circular cover in 15
the form of disk A, having a central opening
B, around which, upon the under surface of
said disk, is a depending ring C, whose verti-
cal walls taper slightly from top to bottom.

The design of the under surface of the cover
is completed by a horizontal ring D, surround- 20
ing the upper end of ring C and the central opening B. The outer edge of said ring D is
at an angle to the under surface of said disk
A, and the upper surface of said ring D is in
contact with the under surface of said disk.

I claim as my invention—

The design for a cover for ice-cream tubs,
substantially as shown and described.

In witness whereof I have hereunto set my
hand, this 15th day of June, A. D. 1898, at
Minneapolis, Hennepin county, Minnesota. 30

ARTHUR H. IVES.

In presence of—

RICHARD PAUL,
A. C. PAUL.
